UNITED STATES PATENT OFFICE.

HARRY S. CLEVELAND, OF MINNEAPOLIS, MINNESOTA.

REFRIGERATOR.

Application filed July 12, 1926. Serial No. 121,867.

My invention has for its object to provide a refrigerator of simple construction and generally increased efficiency; and, generally stated, it consists of the novel devices, combinations of devices, and arrangement of parts hereinafter described and defined in the claims.

In refrigerators, high efficiency requires rapid circulation of the air, first downward from the ice chamber and then upward through the provision chamber and back to the top or upper portion of the ice chamber. In practice, it has been found that the more rapid the circulation, the greater is the tendency to cause the cold air to take a short circuit through the provision chamber closely under the bottom of the ice chamber, so that in spite of the fact that the coldest air tends to drop, the coldest air does not really reach the bottom of the provision chamber.

In the use of refrigerators, it is not only customary but the most convenient practice to place the most perishable food articles on the bottom of the provision chamber, and it follows from this and for other reasons that the best results can be obtained by causing the cold air to pass directly from the cold air discharge flues at the bottom of the ice chamber downward to and over the bottom of the provision chamber; and it is to the attainment of this result that my present invention is chiefly directed. Such object is accomplished by the use of air deflectors that depend from the bottom of the ice chamber in such association with the cold air discharge flues that they will direct the downwardly moving cold air and start the same well on its way toward the bottom of the provision chamber.

A refrigerator involving the invention is illustrated in the accompanying drawings, wherein like characters indicate like parts throughout the several views.

Referring to the drawings:

Fig. 1 is a transverse vertical section taken through the refrigerator on the line 1—1 of Fig. 2; and

Fig. 2 is a horizontal section taken approximately on the line 2—2 of Fig. 1.

The case 3 of the refrigerator may be assumed to be of the usual insulated and metal or porcelain-lined structure, provided with the customary doors 4 and 5 and having the customary ice chamber 6, provision chamber 7 and provision-supporting shelves 8. As here shown, the lining at the bottom of the

ice chamber 6 is designed to afford a drip pan 9 over which is supported an ice rack 10 adapted to support a cake of ice y in the usual way. The vertical inner wall of the ice chamber 6 has a large return flue 11. In the bottom of the ice chamber 6, at its intermediate portion but preferably to one side of its center, is a main cold air discharge flue 12; and in said bottom, adjacent to the outer side wall of the case 3, is a narrow elongated auxiliary cold air discharge flue 13. The flues 12 and 13 are formed by metallic sheets that extend above the bottom of the drip pan 9 so that water cannot run downward therethrough from the drip pan.

An inclined deflecting plate 14, preferably of sheet metal, is attached to the bottom of the ice chamber 6 and extends obliquely under the main flue 12 toward the adjacent side wall of the case or, in other words, toward that side of the case against which the auxiliary flue 13 is located. A deflecting plate 15, also preferably of sheet metal, is attached to the bottom of the ice chamber 6 and extends vertically downward from the inner wall of the auxiliary cold air discharge flue 13. These two deflectors 14 and 15 cooperate to cause the cold air to continue its direct downward passage from the flues 12 and 13 and to acquire such velocity that all of the cold air will be directed further downward than would be the case with the deflectors removed and, moreover, to cause considerable of the cold air to move against and over the very bottom of the provision chamber, or substantially as indicated by the arrows marked on Fig. 1.

This improved circulation insures the lowest temperatures at or closely to the bottom of the provision chamber where the most perishable foods should be and usually are placed. Moreover, this complete circulation, including circulation over the bottom of the provision chamber, prevents accumulation of moisture on the bottom of said provision chamber and renders the air not only as cold but as dry as is possible in a refrigerator using ice. The air is caused to come in contact with all of the free moisture contained in the refrigerator, as well as moisture directly contained on the food articles and, hence, absorbs such moisture, carries the same upward and back into the ice chamber where such moisture will be condensed, precipitated and commingled with the moisture in the drip pan, and from thence carried off

through the customary drain pipe 16 and deposited in a water pan 17 or elsewhere outside of the refrigerator.

To keep the ice cake from coming in contact with the outer wall of the ice chamber and thereby obstructing the flow of the cold air downward through the flue 13, I provide a heavy screen 18 that is slightly spaced from said wall and held in position by hook-like screws 19.

The refrigerator described is of as simple construction as any of the approved standard refrigerators and the additional cost of the deflectors is extremely small and, in fact, a negligible item in the total cost of the refrigerator. Of course, the refrigerator may be made in various different grades, sizes and more or less expensive designs and, moreover, a refrigerator coil or other mechanical refrigeration may be substituted for the ice in the compartment herein for convenience designated as the "ice chamber".

The expression "ice chamber", in this specification and in the claims, is used for convenience to designate broadly a chamber in which the low temperature is produced and would include, for example, a chamber in which the coils or other refrigerating elements of a mechanical refrigerating system are employed. It will also be understood that so far as the broad features of the invention are concerned, the refrigerator may take all sorts of forms and might, for example, be in the form of a butcher's refrigerating counter designed either to contain ice or refrigerating coils.

What I claim is:

1. A refrigerator comprising a case having therein an ice chamber located above its bottom and at one side of the upper portion of its provision chamber, said ice chamber having in its bottom at least two cold air ports spaced transversely the one being closer to the outer wall of the ice chamber than the other, and deflectors applied to and depending from the bottom of said ice chamber, both deflectors directing the cold air into the same provision chamber of said case, the one directing the cold air downward close to the outer wall of said case and the other directing the cold air toward the outer or first noted deflector.

2. A refrigerator comprising a case having therein an ice chamber located above its bottom and at one side of the upper portion of its provision chamber, said ice chamber having in its bottom at least two cold air ports spaced transversely the one being closer to the outer wall of the ice chamber than the other, and deflectors applied to and depending from the bottom of said ice chamber, both deflectors directing the cold air into the same provision chamber of said case, the one directing the cold air downward close to the outer wall of said case and the other directing the cold air toward the outer or first noted deflector, the first noted deflector being extended downward into the provision chamber much farther than the second noted deflector.

In testimony whereof I affix my signature.
HARRY S. CLEVELAND.
